Specification of Letters Patent. Patented May 31, 1921.

Application filed March 17, 1920. Serial No. 366,620.

(FILED UNDER THE ACT OF MARCH 3, 1883, 22 STAT. L., 625.)

To all whom it may concern:

Be it known that I, CLARENCE A. COOK, of the Ordnance Department, United States Army, a citizen of the United States, and 5 a resident of Davenport, county of Scott, State of Iowa, have invented an Improvement in End Clips, of which the following is a specification.

The invention described herein may be 10 used by the Government, or any of its officers or employees in prosecution of work for the Government, or by any other person in the United States, without payment to me of any royalty thereon.

15 This invention relates to a new form of end clip for binding webbing and the like and to the process by which the end clip is shaped and applied to the webbing.

It has been found that by making the 20 closed portion of the initial cup-shaped clip flat instead of curved, and upon pressing such a clip on the webbing, an inward curved portion is automatically formed which tends to compress the webbing within the clip 25 thereby aiding materially in securely fastening the clip to the webbing.

In the following specification reference is made to the accompanying drawings, in which:—

30 Figure 1 is a side elevation of the webbing such as a woven belt with the cup-shaped clip in initial position thereon, the clip shown in section.

Fig. 2 is a side elevation of the webbing 35 with the clip partially compressed;

Fig. 3 is a side elevation of the clip completely compressed to final position; and

Fig. 4 is a sectional view of the webbing and clip shown in Fig. 3.

40 The numeral 1 represents a strip of woven fabric or the like such as is commonly used in making belts, straps, etc. The numeral 2 designates the end clip for such a strip in its initial drawn condition.

45 The first operation in accomplishing my invention is that of drawing a piece of brass, or other suitable material, preferably by means of a die of such shape as to produce a cup shaped clip like that shown in Fig. 1, and then bending the open end of the cup inward. It will be noted that the clip

2 resulting from this operation is formed with a flat base 3, and with the annular sides 4 at approximately right angles to the base and also that the end of the sides or body 5 portion 4 is bent inward by spinning or otherwise so as to form an inturned edge or tooth 5 for engaging the fabric. The end of the strip of fabric is folded over as indicated at 6 so as to fit within the mouth of 60 the cup-shaped clip. Pressure is now applied to the annular surface 4 preferably in a direction at right angles to the direction indicated by the arrows (Fig. 1) so that the cup-shaped clip will be flattened and the 65 opening in the cup elongated.

Fig. 2 illustrates an incomplete result of this pressing operation and it will be noted that the fold 6 of the fabric is flattened out so as to fill the space provided by the elongation of the opening in the cup. A further pressure gives the result shown in Figs. 3 and 4, the tooth 5 being pressed into the webbing and the flat portion 3 of the cup being folded inward as shown at 3', (Fig. 75 4) which compresses the fabric between the end of fold 3' and the tooth 5. This gives the clip a very firm grip on the fabric by increasing the density thereof between the fold 3' and tooth 5 so that it is almost impossible to pull the clip from the fabric without first tearing the same.

Having thus described my invention, what I claim as new and desire to secure by Letters Patent, is:

1. The process of securing a clip to a strip of woven material which consists in forming a piece of metal into a cup-shaped clip having a flattened closed end, inserting a folded end of the strip into the open end 90 of the clip and compressing the metal until the flattened end portion is folded inwardly.

2. The process of securing a clip to a strip of woven material which consists in forming a piece of metal into a cup-shaped clip 95 having a flattened closed end, bending inwardly the terminal edge at the open end of the clip, inserting a folded end of the strip into the clip and compressing the metal until the flattened end portion is folded inwardly against the material included within the clip.

3. An end clip for woven material which comprises a cup shaped body portion having a flattened closed end and the periphery of the open end spun inwardly.
- 5 4. An end clip for woven material comprising a cup shaped member having a flattened closed end and an inwardly spun edge

at its open end, the closed end adapted to buckle inwardly when the clip is flattened upon the material.

5. An end clip for fabrics having a closed end folded inwardly between the sides of the clip.

CLARENCE A. COOK.
